UNITED STATES PATENT OFFICE.

AUGUST E. KIPP, OF DAYTON, OHIO, ASSIGNOR TO THE HOLDEN MANUFACTURING COMPANY, OF SAME PLACE.

BLANK BOOK.

SPECIFICATION forming part of Letters Patent No. 276,601, dated May 1, 1883.

Application filed June 21, 1882. (No model.)

To all whom it may concern:

Be it known that I, AUGUST E. KIPP, a citizen of the United States, residing at Dayton, in the county of Montgomery and State of Ohio, have invented a new and useful Improvement in Blank Books, of which the following is a specification.

My invention relates to the manner of securing the leaves; and it consists in dividing the sheets of paper in two equal or nearly equal parts, and pasting to one part a folded fly-leaf, so that this folded part shall extend beyond the center of the sheets; then lay onto this the other part; then pierce and sew together; then fold each part on itself, thus bringing the fly-leaves to the outside, the objects being to secure the sheets with the least labor, and to save waste from trimming. I attain these objects by the construction illustrated in the accompanying drawings, in which—

Figure I is a transverse section of the book-leaves. Fig. II is a front view of the same before folding.

Like letters designate like parts throughout both views.

A represents the upper and A' the lower series of sheets of paper. B B', to the right, represent the ends of the folded sheet, which

constitute the fly-leaves of the blank book, 30 and to the left the same letters of reference designate the position of the same when folded, as indicated by dotted lines. The inclosed dotted lines show the folding of the two series of sheets. C represents a stout strip of 35 paper pasted to the center of the fly-leaf sheet, for the purpose of strengthening the same at the fold. When the several parts are placed in position, as represented at Fig. I, they are sewed together on the line x, and when folded, 40 as represented by the dotted lines, Fig. I, the leaves are in condition for the attachment of the cover. Fig. II shows the position of the fly-leaf and the stitching. Thus constructed the whole are firmly stitched together, and, 45 folding double instead of single, the waste from trimming the edges is less.

Having fully described my invention, what I claim as new, and desire to secure by Letters Patent, is—

In a blank book, the divided leaves, laid between which is a folded sheet for fly-leaves, the whole being stitched and folded in the manner substantially as set forth.

AUGUST E. KIPP.
